UNITED STATES PATENT OFFICE.

NEWELL A. MCKELVEY, OF BATTLE CREEK, MICHIGAN, ASSIGNOR TO GENERAL ELECTRIC COMPANY, A CORPORATION OF NEW YORK.

OPERATING MECHANISM FOR ELECTRIC CONTROLLERS.

1,275,061.

Specification of Letters Patent.

Patented Aug. 6, 1918.

Application filed August 18, 1914. Serial No. 857,337.

To all whom it may concern:

Be it known that I, NEWELL A. MCKELVEY, a citizen of the United States, residing at Battle Creek, county of Calhoun, State 5 of Michigan, have invented certain new and useful Improvements in Operating Mechanism for Electric Controllers, of which the following is a specification.

This invention relates to devices for controlling a high potential current by means 10 of hand operated mechanism including an oil switch. The controller is intended especially for starting and stopping large induction motors of the slip ring type having outside resistance in the primary circuit. My invention aims to provide a controller in which the high tension primary circuit is closed and opened by an oil switch, using the ordinary controller contacts 15 merely for cutting out the resistance from said circuit after the oil switch has closed, and for cutting in said resistance before opening the circuit at the oil switch. By this means, considerable loss from the burning 20 out of controller contacts can be saved. My invention also includes a novel construction of the operating mechanism for the oil switch which gives it a quick or "snap" 25 action both in closing and opening, and the parts remain locked until released by this 30 operation of the mechanism. Back lash or rebound is guarded against, and a positive, reliable service is assured.

The specific construction of my improved 35 controller and the novel features thereof will be better understood by reference to the following detailed description taken in connection with the accompanying drawings in which

40 Figure 1 is an end elevation of the operating mechanism and the contacts of the oil switch; Fig. 2 is a side elevation, partly in section, of the operating mechanism; Fig. 3 is a perspective view of the intermittent pinion partly broken away; Fig. 4 is a side elevation of a controller embodying my invention; Fig. 5 is a perspective view of the operating mechanism, partly broken away; Fig. 6 is a cross section on the line 6, 45 Fig. 2; Fig. 7 is a cross section on the line 7, Fig. 2; Figs. 8 and 9 are diagrams illustrating the operation of the parts; Fig. 10 is a longitudinal section of the cam shaft 50

and the parts it carries; and Fig. 11 is a longitudinal section of the spring plunger. 55

The controller 1 has the usual upright shaft 2 rotated by a handle 3 and carrying the contact drum (not shown). At some convenient point it is provided with a bevel gear 4 meshing with a bevel pinion 5 on a horizontal shaft 6 which extends beyond the back of the controller and actuates the parts which make up the oil switch operating mechanism. On the overhung end of the shaft 6 is an intermittent pinion comprising 60 a hub 7 carrying two crank arms 8, 8' between which is a crank pin 9 provided with an antifriction roller 10. At each end of the hub 7 is a circular disk 11, 11' having a mutilated flange 12, 12', the two flanges 65 extending in opposite directions from their respective crank arms for about three-fourths of the circumference of their disks, and terminating in rounded noses 13. The crank pin engages in a notch 14 in the upper end of a yoke 15 whose hub 16 is keyed to a cam shaft 17 parallel with and below the pinion shaft. A bracket 18 secured to the back of the controller provides one bearing 19 for the cam shaft, while its other end is journaled in a pillow block 20 supported by the bracket. 70

On each side of the yoke and located respectively on its front and back are lugs 21, 21' adapted to be engaged by the flanges 12, 12' respectively when the yoke is oscillated to one side or the other by the crank pin. At each end of the yoke is an arm 22, 22' extending parallel with the cam shaft and preferably provided with a slightly concave 75 inner surface 23.

Adjacent to the yoke is an oscillating actuating member for the switch contacts. This oscillating member comprises a rocker whose hub 24 is loosely mounted on the cam shaft 17 so as to turn independently thereof. The rocker is bifurcated, and in each of its arms 25, 25' is a hole to receive a biased plunger, which is preferably composed of a rod 26 having heads 27, 27' secured to its ends, said heads having a sliding fit in the holes in the arms. Before the heads are put on, thimbles 28, 28' are slipped over the rod, and the heads abut against the inner ends of said thimbles. At the 100 outer ends of the thimbles are flanges 29

which rest against the arms 25, 25', and between said flanges is confined a helical compression spring 30 which encircles the thimbles and the rod. In the outer end of each 5 head 27, 27' is an antifriction roller 31. One side of the head 27' is flattened at 32 to coöperate with a pin 33 in the arm 25' and keep the plunger from rotating in the holes in the rocker arms. The plunger is 10 biased to the mid-position and is capable of being reciprocated in a tangent to an arc of oscillation of the rocker so as to exert a torque on the rocker.

On one side of the rocker is a lug 34 to 15 which is pivoted the upper end of a rod which actuates the contacts of the oil switch. The rod is adjustable in length, preferably as shown in Figs. 1 and 2, where the eye 35, which is pivoted to the lug 34 by a pin 20 36, has a screw-threaded socket 37 receiving one end of a coupling 38 provided with right and left hand screw threads. The other end of the coupling screws into a socket 39 which has a transverse dovetail 25 groove 40 to engage with the dovetailed upper end of a bar 41 of wood or other insulating material. Lock nuts 42 secure the parts when the coupling has been adjusted by turning it by means of the polygonal collar 30 43.

Suitably secured to the under side of the hub 24 of the rocker is a sector-shaped stop 44 preferably semicircular and having two steps or shoulders 45, 46, 45', 46' on each 35 side. Two pawls or dogs 47, 47' are pivoted at 48, preferably to the pillow block 20, and each pawl coöperates with one set of steps. A helical spring 49 connects the two pawls and keeps them yieldingly engaged 40 with both sides of the stop. Each pawl is held positively in place by a latch 50, 50' pivoted at 51 and having a stepped lip 52, preferably of hardened steel, whose lower step normally abuts against the back of the 45 pawl. The rocker is thus locked against angular movement in either direction until one or the other of the pawls is released.

To effect the tripping of a latch and the release of its pawl, each latch has a trigger 50 53, 53', preferably offset from the plane of the stop to lie in the plane of a cam plate 54 secured to the cam shaft 17, and having on each edge two inclined cam surfaces 55, 56, 55', 56'. The triggers normally rest on surfaces 57, 57' concentric with the shaft 17, but will be actuated by these cam surfaces when the cam plate is oscillated. A tension spring 58" connects the two triggers.

The rod 41 is pivoted at its lower end to 60 an arm 58 on a shaft 59 which carries the movable contacts 60, 60' of the oil switch; the one shown having three contacts to handle a three phase line. These contacts are the fixed contacts 61, 61', with which they 65 coöperate, are inclosed in an oil tank 62 sus-

pended from the bracket 18. The contacts 60 are carried preferably on arms 63 pivoted to the support 64 which is clamped to the shaft 59. A spring 65 inserted between lugs 66, 67, on the arm and support respectively, 70 gives the contact a yielding and wiping closure upon the stationary contact 61. Flexible conductors 68 connect the arms with the support, and other similar conductors 69 connect the support with the connection 75 board 70 at the top of the switch.

The operation is as follows: When the controller handle 3 is rotated, the bevel gears 4, 5 impart a rotation to the pinion shaft 6 and cause the intermittent pinion, 80 whose crank pin engages the notch 14 in the yoke 15, to rock said yoke to one side or the other; say to the right in Figs. 6 and 7. The arm 22 forces the plunger to the right and compresses the spring 30 (Fig. 8), 85 which exerts a strong pressure against the arm 25' of the rocker, but no motion thereof results because it is locked by the pawls and latches. However, with the rocking of the yoke, the cam shaft 17 is oscillated, because the yoke is keyed thereto. This movement swings over the cam plate 54, whose surface 57' slides down under the trigger 53' until the cam surface 55' reaches the trigger; whereupon the latter is lifted and 90 its latch 52 is withdrawn from the pawl 47'. Since the surface 45' is oblique to the radius of the shaft 17 it will act as a cam, and the downward thrust given to this side of the stop 44 by the compressed spring 30 acting 100 against the rocker arm 25' will cause said surface 45' to force the pawl 47' back and let the rocker snap over to the right, pushing down the rod 41 and closing the left-hand pair of contacts 60, 61. The operating 105 mechanism now occupies the position shown in Fig. 9; the rocker and plunger standing midway of the yoke as in Fig. 6 with the spring 30 under only normal compression. The stop, however, has its step 46 resting 110 on the pawl 47, and the upper step of the lip 52 on the latch 50 has dropped in behind said pawl to lock it; the shorter radius of the cam below the cam surface 56 permitting the trigger 53 to move inwardly sufficient to let the latch assume this position. 115

About the time the crank pin of the intermittent pinion leaves the notch 14 in the yoke, the nose 13 of the flange 12 enters beneath the lug 21, and prevents any backward rotation of the yoke and cam plate or any rebound of the parts when the spring snaps the rocker to its new position. It also holds the yoke in position for the crank pin to re-enter the notch 14 when it returns upon a 120 reversal of the direction of rotation of the controller handle; which must have a considerable angular range in addition to that required to operate the oil switch in order to enable it to cut out the resistance in the 125 130

primary circuit of the induction motor by a continuation of the movement of the controller handle after the oil switch contacts have been closed.

- 5 When the circuit is to be opened, the controller handle is turned backward, and presently the crank pin engages the notch in the yoke, and swings it back to its horizontal position again, compressing the spring 30
 10 in the opposite direction to that previously effected. The cam plate, oscillating with the yoke, pushes back the trigger 53 and releases the pawl 47 from the shoulder 46 so that the torsion on the rocker exerted by the spring 30 can throw the rocker and the stop 44 back to the horizontal "off" position in which they are shown in Fig. 1, and thereby, through the rod 41, open the oil switch. The pawl 47 moves back only far
 15 enough to catch the shoulder 45 when the stop turns, and at the same instant the pawl 47 snaps in under the shoulder 45 and the latches drop into their normal position so that the rocker is positively arrested and
 20 held.

If the motor is to run in the opposite direction, the controller handle is turned backward, beyond the "off" position, swinging the yoke over to the left and causing the
 25 rocker to snap over in that direction and close the oil switch contacts 60', 61'.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by
 30 other means.

What I claim as new and desire to secure by Letters Patent of the United States, is,

1. A quick action switch operating means comprising a biased plunger resiliently connected to a contact member and so positioned with respect thereto that a movement of the plunger against its bias exerts a force tending to move the contact member, means for normally restraining the movement of the
 45 contact member from a predetermined position, means for moving the plunger against its bias, and means for releasing the said contact member so as to be moved quickly to another predetermined position responsive to the force exerted by the said movement of the plunger against its bias.

2. A quick action switch operating means comprising an oscillating actuating member connected to a movable switch contact member, means for normally restraining the movement of the actuating member from a predetermined position, a biased plunger carried by the actuating member, movable with respect thereto and so positioned as to exert a torque on the actuating member when

moved, means for moving the plunger against its bias, and means for releasing the actuating member to move the switch contact member quickly to another predetermined position responsive to the torque exerted by the said movement of the plunger against its bias. 70

3. A quick action switch operating means comprising an oscillating actuating member connected to a movable switch contact member, means for restraining the movement of the actuating member from a predetermined position, a biased member resiliently connected to the actuating member and positioned with respect thereto so as to move in 75 a tangent to an arc of oscillation of the actuating member and exert a torque thereon, means for moving the biased member against its bias so as to exert a torque on the actuating member, and means for releasing the actuating member to move the switch contact member responsive to the torque exerted by the biased member. 80

4. A quick action switch operating means comprising a rocker connected to a movable switch contact member and normally restrained from movement from a predetermined position, a biased member carried by the rocker movable with respect thereto and so positioned as to exert a torque on the 90 rocker when moved, means for moving the said member against its bias so as to exert a torque on said rocker, and means for releasing the rocker to move the switch contact member to another predetermined position 95 responsive to the bias of said member. 100

5. A quick action switch operating means comprising a bifurcated member operatively connected to a movable switch contact member, a plunger supported by the arms of the 105 bifurcated member, a spring between said arms adapted to be compressed by a longitudinal movement of the plunger so as to exert a force tending to move the contact member, means for normally restraining the movement of the contact member from a predetermined position, means for imparting a longitudinal movement to the plunger, and means for releasing the said contact member so as to be moved quickly to another pre- 110 determined position responsive to the compression of the spring. 115

6. A quick action switch operating means comprising a rocker adapted to be connected with a movable switch member, means for 120 normally restraining said rocker from movement from a predetermined position, a spring plunger carried by said rocker, means for exerting a pressure on said plunger to exert a torque on said rocker, and means for 125 releasing the rocker to move the switch contact member responsive to the pressure on the plunger.

7. A quick action switch operating means comprising a bifurcated rocker adapted to 130

- be connected with a movable switch contact member, means for normally restraining the rocker from movement, a plunger supported by the arms of said rocker, a spring between said arms adapted to be compressed by a longitudinal movement of said plunger, means for imparting said movement, and means for releasing the rocker to move the switch contact member when the spring has been compressed.
8. A quick action switch operating means comprising a bifurcated rocker adapted to be connected with a movable switch contact member, means for normally restraining the rocker from movement from a predetermined position, the said rocker having holes in its arms, a plunger sliding in said holes, a spring encircling said plunger between said arms, means carried by said plunger for compressing said spring, means for sliding said plunger lengthwise to compress the spring, and means for releasing the rocker to move the switch contact member to another predetermined position responsively to the compression of the spring.
9. A quick action switch operating means comprising a bifurcated rocker adapted to be connected with a movable switch contact member, means for normally restraining the movement of the rocker from a predetermined position, the said rocker having holes in its arms, a plunger sliding in said holes, thimbles on said plunger, a spring compressed between said thimbles by the sliding of the plunger, means for sliding the plunger lengthwise, and means for releasing the rocker to move the switch contact member to another predetermined position responsively to the compression of said spring.
10. A quick action switch operating means comprising a rocker, means for normally restraining the rocker from movement from a predetermined position, a plunger moving in a tangent to an arc of oscillation of said rocker, a spring adapted to be compressed by said plunger, means for putting pressure on the plunger to compress the spring, means for releasing the rocker to move to another predetermined position responsively to the compression of the spring, and means for communicating the movement of the rocker to the switch contacts.
11. Operating means for a quick action switch, comprising a rocker adapted to be connected to a movable switch contact member, means for normally restraining the movement of the rocker from a predetermined position, a biased member resiliently connected to the rocker and movable with respect thereto so as to exert a torque on the rocker when the said biased member is moved against its bias, means pivoted coaxially with the rocker for moving the biased member against its bias, and means for releasing the rocker to move to another predetermined position responsively to the torque exerted by the biased member.
12. A quick action switch operating means comprising a rocker, means for normally restraining the rocker from movement from a predetermined position, a spring plunger moving in a tangent to an arc of oscillation of said rocker and capable of exerting a torque on the rocker, a yoke pivoted coaxially with said rocker, and having arms adapted to engage the ends of said plunger, means for releasing the rocker to move to another predetermined position responsively to the torque exerted on the rocker by the spring plunger, and means for communicating the movement of said rocker to the switch contacts.
13. A quick action switch operating means comprising a rocker, means for normally restraining the rocker from movement from a predetermined position, a spring plunger moving in a tangent to an arc of oscillation of said rocker and capable of exerting a torque on the rocker, a yoke pivoted coaxially with said rocker, and having arms adapted to engage the ends of said plunger, a rotatable shaft, means whereby said shaft can oscillate said yoke to compress the spring associated with said plunger, means for releasing said rocker to move to another predetermined position responsively to the compression of said spring, and means for communicating the movement of said rocker to the switch contacts.
14. A quick action switch operating means comprising a rocker, means for normally restraining the movement of the rocker from a predetermined position, a spring plunger moving in a tangent to an arc of oscillation of said rocker and capable of exerting a torque on the rocker, a yoke pivoted coaxially with said rocker, and having arms adapted to engage the ends of said plunger, a rotatable shaft, a crank pin on said shaft engaging said yoke for moving the spring plunger, means for releasing the rocker to move to another predetermined position responsively to the torque exerted by the spring plunger, and means for communicating the movement of the rocker to the switch contacts.
15. A quick action switch operating means comprising a rocker, means for normally restraining the rocker from movement from a predetermined position, a spring plunger moving in a tangent to an arc of oscillation of said rocker and capable of exerting a torque on the rocker, a yoke pivoted coaxially with said rocker and having arms adapted to engage the ends of said plunger, a rotatable shaft, a crank pin on said shaft engaging said yoke for moving the spring plunger, means for interlocking said shaft and yoke during a portion of the rotation of said shaft, means for releasing the rocker to move to another predetermined position responsively to the torque exerted by the spring plunger.

to move to another predetermined position responsively to the torque exerted by the spring plunger, and means for communicating the movement of the rocker to the switch contacts.

16. A quick action switch operating means comprising a rocker, means for normally restraining the movement of the rocker from a predetermined position, a spring plunger

10 moving in a tangent to an arc of oscillation of said rocker and capable of exerting a torque on said rocker, a yoke pivoted coaxially with said rocker and having arms adapted to engage the ends of said plunger,

15 a rotatable shaft, a crank pin on said shaft engaging said yoke for moving the spring plunger, lugs on said yoke, disks on said shaft having mutilated flanges to engage with said lugs during a portion of the rotation

20 of said shaft, means for releasing the rocker to move to another predetermined position responsively to the torque exerted by the spring plunger, and means for communicating the movement of the rocker to the switch contacts.

17. A quick action switch operating means comprising a shaft, a rocker mounted thereon, a spring plunger connected to the said rocker, movable in a tangent to an arc of

30 oscillation of said rocker and capable of exerting a torque thereon, a shouldered sector-shaped stop secured to said rocker, pawls engaging said stop, means for locking said pawls to restrain the movement of the rocker,

35 means for unlocking the said pawls, means for exerting pressure on the plunger to cause movement of the rocker when the said pawls are released, and means for communicating the movement of said rocker to the switch contacts.

18. A quick action switch operating means comprising a shaft, a rocker mounted loosely thereon, a spring plunger connected to said rocker, movable in a tangent to an arc of

40 oscillation of said rocker and capable of exerting a torque thereon, a yoke secured to said shaft and coöperating with said plun-

ger, a shouldered stop secured to said rocker, pawls engaging said stop to restrain movement of said rocker, latches for locking said pawls, means for releasing said latches to permit movement of the rocker responsively to the torque exerted by the said spring plunger, and means for communicating the movement of said rocker to the switch contacts.

19. A quick action switch operating means comprising a shaft, a rocker mounted loosely thereon, means for connecting the rocker to a movable switch contact member, a 60 spring plunger movable in a tangent to an arc of oscillation of said rocker and capable of exerting a torque thereon, a yoke secured to said shaft and coöperating with said plunger, a shouldered stop secured to said 65 rocker, pawls engaging said stop, latches for locking said pawls, triggers on said latches, and a cam plate on the shaft engaging with said triggers for releasing the rocker to move responsively to the torque 70 exerted by the spring plunger.

20. A quick action switch operating means comprising a shaft, a rocker mounted loosely thereon, means for connecting the rocker to a movable switch contact member, a spring 75 plunger movable in a tangent to an arc of oscillation of said rocker and capable of exerting a torque thereon, a yoke secured to said shaft and coöperating with said plunger, a shouldered stop secured to said rocker, 80 pawls engaging said stop, latches for locking said pawls, stepped lips on said latches, triggers for releasing said latches, and a cam plate having two successive cam surfaces engaging with said triggers for releasing the rocker to move responsively to the torque exerted by the spring plunger.

In witness whereof, I have hereunto set my hand this 14 day of Aug., 1914.

NEWELL A. MCKELVEY.
